United States Patent Office.

OSCAR S. BURGES, SR., OF BATTLE CREEK, MICHIGAN.

Letters Patent No. 99,836, dated February 15, 1870.

IMPROVED WASHING-MACHINE.

The Schedule referred to in these Letters Patent and making part of the same.

To all whom it may concern:

Be it known that I, OSCAR S. BURGES, Sr., of the city of Battle Creek, in the county of Calhoun, and State of Michigan, have invented a certain new and useful Improvement in Combined Water-Heating, Steam-Generating, and Washing-Machines; and I do hereby declare that the following is a full, clear, and exact description of the same, reference being had to the accompanying drawings, and to the letters of reference marked thereon.

In the drawings—

Figure 1 is a perspective view of the machine, with its top cover raised, showing its interior.

Figure 2 is a perspective view of the movable fire-box.

Figure 3 is a vertical section of the slatted cylinder, showing the manner of arranging the bucket-shaped slats *a*.

This invention relates to that class of clothes-washing machines having a slatted cylinder, into which the clothes are placed while the cylinder is suspended within a reservoir or chamber of hot water and steam, the requisite heat being supplied by means of a fire underneath.

The nature of this invention consists—

First, in providing the cylinder with slats that shall offer the least possible resistance to the free passage of the largest quantity of water between them, those slats being placed at an angle of about forty-five degrees from a line drawn perpendicularly through the center of the ends of the cylinder, one-half of these slats standing in one, and the other half in the opposite direction throughout the entire circumference of the cylinder, so that when it is rotated or given a reciprocating movement, the water is gathered in or lifted up and directed toward the centre of the cylinder, and thereby brought into contact with all its contents.

Second, in providing a fire-box that may be easily and quickly removed from the reservoir, for the purposes of simplifying the machine, reducing the cost of construction and repair, and securing other obvious advantages.

Third, in providing a steam conductor and an adjustable platform, for the purpose of instantly converting the washing-machine into a steamer and water-heater, applicable to the various culinary, bath-room, and other purposes for which steamers are ordinarily used.

Fourth, in the peculiar construction and arrangement of the various parts comprising the machine, whereby an efficient and entirely portable water-heater, steam-generator, and washing-machine is combined in one apparatus.

In order to enable those skilled in the art to make

and use my invention, I will now proceed to describe its peculiar construction and operation.

A, fig. 1, represents a rectangular box or reservoir, supported by four posts or legs, giving the whole a convenient elevation, and provided with an outlet-pipe and faucet, *c*, fig. 1, near its bottom, for the purpose of drawing off the water. The bottom of the reservoir is made of sheet metal, copper being preferred, while its sides and ends should be lined, either partially or wholly, with any suitable metal.

On the inside of this reservoir or chamber A, at suitable points for permitting the cylinder to revolve without touching the bottom of the chamber, and on either side of the same, are placed rests for the axis of the cylinder, one side of the box A being pierced at this point for the insertion of the shaft of the crank *d* into the surface opening provided in the end of the cylinder for the purpose of revolving the same.

B represents the slatted cylinder, the manner of its construction being clearly shown in fig. 3.

The slats *a*, composing the circumference of the cylinder, I prefer to make of zinc or copper, but they may be made of any other material. They are placed at an angle of about forty-five degrees from a line drawn perpendicular to the center of the cylinder, with about every six of the slats standing in opposite directions, or the one-eighth part of the whole number in one, followed by an equal proportion in the opposite direction. The slats may be attached to the heads or ends of the cylinder by means of nails, or they may slide in grooves cut in the heads for that purpose, and the heads and several parts firmly and securely held together by means of the stay-rods *b*, fig. 3, the latter being provided with suitable shoulders on their inner, and flanges on their outer ends, through which and into the ends of the rods screws *m* pass for that purpose. The slats are attached together by means of the braces *g*, fig. 1.

C represents a sheet-iron fire-box, open at top, fig. 2, and provided with suitable flanges and other means for instantly attaching it to the under surface of the sheet metal bottom of the box A, the bottom of the latter serving, also, for the top of the fire-box. A pipe in the rear end of the fire-box serves to secure a draft for the fire by conveying the products of combustion upward and wherever desired.

D represents a cover for the chamber A, fitting its top nicely, and provided with a flange on its inner side, extending downward, for the purpose of retaining the condensation of the steam and vapor within the reservoir.

An outlet-pipe, *d*, with faucet *f*, is provided to this cover, for the purpose of retaining the steam within the chamber, or discharging it therefrom whenever desired.

A platform, *h*, is attached to the legs on the side of the box *A*, by means of bolts or screws 1 2, forming joints, so as to admit of the platform being folded up against the side of the reservoir when not in use.

The platform is for a stand or rest, on which to place any vessel containing water to be heated or substance to be steamed, the steam being conducted thereto by means of the pipe *d*.

The mode of operating this machine as a washing-machine differs in no essential particular, perhaps, from that of other analogous machines.

After the water has become sufficiently heated by a fire in the box *C*, the clothes, suitably prepared with soap, are placed within the cylinder *B*, and the operator agitates the same by imparting a rotating, and, at the same time, an oscillating movement, by means of the crank. This causes the clothes to be kept constantly changing their position, while the peculiar bucket-shaped slats gather up the water and direct it into the cylinder and toward its centre, so that a current of the hottest water in the reservoir is being constantly brought into forcible contact with the clothes, the peculiar form and arrangement of the slats in this machine being such as to offer the least possible resistance to the free and full ingress of the water to the interior of the cylinder throughout its whole length, whether the same is revolved in the one or the other direction, inasmuch as one-half of all the slats are constantly acting in the way and manner described.

If, while washing with this machine, or at any time, we desire to heat water or steam any substance contained in another vessel, all we have to do is to place the vessel on the platform *h*, attach one end of the movable pipe *d* to the faucet in the cover *D*, placing its opposite end beneath the surface of the water in the vessel, open the faucet, and the heating of the water is very expeditiously accomplished, caused by the condensation of the steam thrown off from the chamber *A*. Hot water may also be at any time obtained direct from the reservoir in the usual well-known manner, by means of the faucet in its bottom.

In addition to the advantages already seen to be secured by the use of this machine, may be mentioned

the following, viz: It is a very cheaply constructed, perfectly portable and durable water-heater and steam-generator, quickly put up in any locality where wanted, for heating water for bath-room or any other purpose, while it is so constructed in separate parts that each part may be instantly detached from the rest of the machine, and, hence, cheaply repaired or renewed without incurring the cost of constructing an entirely new machine throughout.

Disclaimer.

I do not claim, broadly, the use of slats in the cylinders of revolving washing-machines; nor do I claim the device of beveling the edge of the slats, where such beveled edges do not extend throughout the entire length of the slats, or where one part of each slat is beveled in one direction and the other is beveled in the opposite direction, as in the "Bisbee" machine, patented August 14, 1866; nor when, as in that machine, the slats occupy the greater portion of the circumference of the cylinder; nor when the dipping surfaces of such beveled slats are confined to one-half of the length of the slats; but

What I do claim, and desire to secure by Letters Patent of the United States, is—

1. The construction and arrangement of the dipping slats *a* and *a'*, ends or heads *B B*, bolts *b*', in combination with reservoir *A*, as shown and described.
2. The arrangement of the pipe *d*, with cover *D*, in combination with tub *a''* and platform *h*, as shown and described.
3. The arrangement of the fire-box *O* and pipe *D'*, in combination with cylinder *B*, reservoir or box *A*, stop-cock *c*, crank *d*, platform *h*, and tub *a'*, all arranged as shown and described.

In testimony that I claim the foregoing, I have hereunto set my hand and seal, this 7th day of January, A. D. 1870.

OSCAR S. BURGES, SEN. [L. S.]
